UNITED STATES PATENT OFFICE.

ALLEN H. ROWE, OF HARTFORD, CONNECTICUT.

DESIGN FOR A HORSESHOE-CALK.

SPECIFICATION forming part of Design No. 26,587, dated February 2, 1897.

Application filed December 18, 1896. Serial No. 616,201. Term of patent 14 years.

To all whom it may concern:

Be it known that I, ALLEN H. ROWE, a citizen of the United States, and a resident of Hartford, in the county of Hartford and State 5 of Connecticut, have invented a new Design for Horseshoe-Calks; and I do hereby declare the following, when taken in connection with the accompanying drawings and the letters of reference marked thereon, to be a full, clear, 10 and exact description of the same, and which said drawings constitute a part of this specification, and represent, in—

Figure 1, a view in side elevation of a horseshoe-calk embodying the design; in Fig. 2, a 15 top view of the calk; and in Fig. 3, a view in side elevation of the calk, showing the base in edge view.

My invention relates to a design for a horseshoe-calk; and it consists in the configuration 20 of the device as hereinafter described, and shown in the accompanying illustrations.

When viewed in side elevation, as shown in Fig. 1 of the drawings, the calk is divided into a cylindrical threaded upper portion *a*, 25 with a distinct groove *b* between this portion *a* and the square base *c*. Below the base *c*

the body portion *d* tapers into the form substantially of a truncated cone. On each side of the base *c* its surface is oblong in general outline, its lower boundary line, however, 30 having a downward-projecting curved part *c'* at about the center of the side.

When seen in edge view, as depicted in Fig. 3 of the drawings, the side lines of the conical body part *d* meet the base at a point 35 within the edge, forming a distinct shoulder *d'*.

An essential feature of this design is the peculiar configuration of the side surfaces of the base, each of which surfaces has the central downward-projecting part extending onto 40 the surface of the conical point immediately below it.

I claim—

The design for horseshoe-calks substantially as herein described and shown. 45

In testimony whereof I have signed this specification in the presence of two subscribing witnesses.

ALLEN H. ROWE.
